CHOKE WITH CONTACTING FINGER AND SLEEVE SURFACES OF CONCENTRIC ARCS

Ewald Schacht, Waseca, Minn.

Filed June 8, 1954, Ser. No. 435,112

3 Claims. (Cl. 42—79)

This invention relates generally to improvements in shotguns and particularly to shot pattern control devices or chokes used therewith.

It is common today to provide the muzzle end of a shotgun barrel with a device for adjustably controlling the pattern of shot mass fired from the gun. Such devices, frequently referred to as variable chokes, normally comprise a tubular shell member fixed to the barrel and having a forward portion adapted to be contracted and expanded to vary the bore diameter of the muzzle end of the barrel. The shell has a plurality of annularly arranged resilient wall segments at its forward end with an adjusting sleeve around the segments for opening or closing the same relative to each other. This is conventionally effected by forwardly tapering the outer surfaces of the segments and providing a tapered mating surface on the sleeve interior so that contraction and expansion of the choke opening is controlled by longitudinal movement of the sleeve. Examples of this construction are very common in the art.

In conventional chokes using the tapered shell such as above mentioned it is necessary that the adjusting sleeve engage the shell segments only along their extended end portions leaving a space between the sleeve and the segments along their inner portions. So constructed the segments do not have adequate backing and become distorted in time rendering the shell ineffective for governing the shot pattern.

Where the tapered shell and cooperating sleeve are used a full backing of the segments by the sleeve proves inoperative. This is due to the fact that when the sleeve is adjusted inwardly to close the choke the sleeve will exert inward radial pressure only upon the inner or rearward portions of the forwardly extending shell segments leaving their extended ends contracted to a position where they are spaced inwardly from and unbacked by the adjustment sleeve. This is due to the fact that the straight taper will attempt to move each segment inwardly the same distance along its entire length while the shell construction demands that to bring about the choke the extended or forward end portions of the segments must move radially inward a greater distance than the inner or rearward portions thereof.

For these reasons, heretofore known variable choke constructions have failed to provide for rigid shell segment backing at all positions of adjustment with the result that the segments have become distorted under force of the shot blast and the choke ultimately becomes ineffective necessitating repair.

It is accordingly the primary object of my invention to provide an improved adjustable choke construction for shotguns wherein the segments of the choke shell will have complete and adequate backing regardless of the adjustment of the choke opening.

Another object of the invention is to provide a shot pattern control device for shotguns which will maintain its accuracy without repair throughout long periods of use.

Still another object of the invention is to provide an adjustable choke device for shotguns, the manual adjustment of which might be made with extreme ease and speed as compared to heretofore known chokes.

5 Still another object of the invention is to provide an improved choke device for shotguns which is extremely durable and yet which is simple in design allowing its manufacture at a relatively low cost.

With the above mentioned objectives in mind, my invention broadly comprises forming the exterior surface of the choke shell segments to curve longitudinally inward toward the forward end thereof, said curve being the arc of a circle, and the interior of the adjustment sleeve having a mating curved surface in flush engagement with said exterior surface of the shell whereby as the sleeve is adjusted longitudinally on the shell the segments will be constantly backed throughout their length by the sleeve.

The above mentioned and still additional objects will 20 be brought to light during the course of the following specification, reference being made to the accompanying drawing, in which:

Fig. 1 is a top plan view of my improved shot pattern control device fixed on the end of a shotgun barrel.

25 Fig. 2 is a longitudinal section of the device taken on line 2—2 of Fig. 1 and showing the choke shell in fully open condition.

Fig. 3 is a longitudinal section similar to Fig. 2 with the choke shell in contracted or full choke condition.

30 Fig. 4 is a transverse section taken on line 4—4 of Fig. 2.

Referring now more particularly to the drawing, reference numerals will be used to denote like parts or structural features in the different views. The muzzle or

35 discharge end of a shotgun barrel is designated by the number 5. I have shown my improved shot pattern control device mounted on the barrel end 5, though it is possible to form the shell member, denoted generally at 6, of the device integral with the barrel if desired.

40 The shell 6 is of generally tubular shape and is fixed to the barrel in axial alignment therewith in any suitable manner as by soldering or screw threading. The number 7 indicates generally a cylindrical adjustment sleeve which fits around the sleeve 6 and which is connected thereto by suitable means, to be later described, allowing the sleeve to be longitudinally adjusted thereon.

In Fig. 1 there is shown a compensator or sleeve 8 threaded on the forward end of sleeve 7. This compensator 8 provides a conventional expansion chamber at the forward end of the gun barrel and has a series of slots 9 therein to allow escape of the expanding gases following the discharged shot mass. The member 8 forms no part of the present invention and is shown merely as exemplary of a manner in which this desirable feature can be employed in connection with the novel choke device herein disclosed.

The inner shell 6 will now be described in greater detail. It has a collar 10 at its inner or rear end adapted to fit snugly around the barrel for attachment thereto.

60 Forward of the collar 10 the shell has a reduced internal diameter which is equal to that of the gun barrel bore. There is a solid annular portion 11 disposed between the collar 10 and the forward constrictable choke portion 12 of the shell. Choke portion 12 has longitudinal slots 14 extending rearwardly from the forward end of the shell which divide the portion 12 into a plurality of annularly arranged forwardly extending segments or fingers 15. The rear end of the choke portion 12 is provided with a peripheral external channel or groove 13, the purpose

65 of which is to reduce the thickness of the shell wall at that point to allow the segments 15 to resiliently give radially inward when external pressure is exerted upon

them. Slits 14 are sufficiently wide to allow a limited amount of such radial movement of all of the segments simultaneously for contraction of the choke portion of the shell.

The external contour of the choke portion 12 and the segments 15 which compose the same is of critical importance to the present invention. The external surface of the portion 12 from the channel 13 on forward is denoted by the numeral 16. This surface is round in transverse cross section on any such section along its entire length. The fore and aft contour of the surface 16 on any diametrical or longitudinal section of the choke portion 12 is convex on an arc which curves inwardly in its forward progression. This arc has its center located preferably near the transverse vertical plane of the rear end of the surface 16. The longitudinal curve is very gradual, as shown, and preferably, although not necessarily, comprises less than ten degrees of the circle used.

The shell 6 is externally threaded as at 17 at a place to the rear of the contractible portion 12. The rear end portion 18 of the adjustment sleeve 7 is internally threaded as at 19, the threads 17 and 19 being in screw threading engagement with each other. This means allows rotation of the sleeve on the shell for longitudinal adjustment of the former. The sleeve 7 may be provided with a partial knurled surface 20 to facilitate its manual rotation.

The forward portion of sleeve 7 forms a wedging means and is designated by the number 22 and the front end thereof is reduced as at 23 and threaded for attachment of the aforementioned compensator 8. The interior surface 24 of the sleeve portion 22 is contoured to mate with the surface 16 of the shell 6. The surface is accordingly concave being round in cross section throughout its length and longitudinally curving inward on an arc having the same center as that of the longitudinal arc described by the immediately adjacent surface 16. It is desirable that the sleeve 7 and its interior surface 24 extend forwardly a slight distance beyond the shell 6 when the choke is in open position as shown in Fig. 2.

The operation of the device will now be clearly understood. When the sleeve 7 is in its forward position (Fig. 2) the internal diameter of the shell or choke tube 6 is constant throughout its length, a diameter equal to the bore of barrel 5. The choke is then in open condition and each segment 15 has complete exterior backing throughout its length by the sleeve portion 22.

To bring the device to a full choke the sleeve 7 is rotated to move inwardly on threads 17 and the portion 22 becomes a wedge with surface 24 exerting radial pressure upon the surface 16. Segments 15 will yield inwardly to bring the shell portion 12 to the contracted condition shown in Fig. 3. The pitch of threads 17 and 19 is preferably coordinated with the shell contour whereby the segments are brought to a full choke position upon one complete revolution of the adjustment sleeve. Obviously the choke opening may be varied by adjusting the sleeve less than one revolution as desired. An indicator scale may be provided on the collar 10 or sleeve portion 18 to aid in proper adjustment.

In adjusting the choke, surface 24 will slide flush along the surface 16 giving complete backing at all positions. Segments 15 resiliently yield primarily at their reduced wall portion 13. When the segments are placed under inward pressure the extended ends of the segments will obviously be moved inwardly a greater distance than will the rearward or attached portions thereof. Thus the greater longitudinally inward pitch of the surface 16 near its extended end is completely compensated for by the like pitch of the forward end area of surface 24.

My invention has two primary advantages which will be readily understood. First with the segments or fingers having uniform and complete backing throughout their length whether in open, full choke, or any position therebetween, they will not become deformed under repeated

shot blasts. This feature obviously renders the choke both accurate and inexpensive to operate over extended periods of use.

A second primary feature of my improved choke construction lies in the ease and speed with which it may be manually adjusted. In conventional chokes where full backing of the fingers is lacking, there is a smaller area of engagement between the choke tube and the wedging surface of the adjustment sleeve. Accordingly there must be considerable pressure exerted at these small areas of contact. This makes rotation of the adjustment sleeve more difficult than in the present construction. In my improved device the wedging pressure is exerted uniformly over the entire outer surface of the finger portion of the choke allowing the choke device to be adjusted with relative ease.

Both of these advantages are a direct result of the exterior longitudinal contour of the forward slotted portion of the shell and the mating interior contour of the adjustment sleeve.

I have accordingly provided an economical and effective shot pattern control device for carrying out the aforementioned objectives. It is understood that suitable modifications may be made in the structure as disclosed, provided such modifications come within the spirit and scope of the appended claims. Having now therefore fully illustrated and described my invention, what I claim to be new and desire to protect by Letters Patent is:

1. In a shot pattern control device for a shotgun, a generally tubular shell for mounting on the forward end of the gun barrel and in axial alignment therewith, said shell having a plurality of annularly spaced slits in the wall thereof extending longitudinally rearwardly from its front end so as to divide the wall into a series of forwardly extending fingers radially contractable under peripheral pressure to constrict the passage through the forward end portion of the shell, a sleeve encircling the shell and secured thereon for longitudinal adjustment with respect thereto, said sleeve having an annular inner surface in peripheral pressure contact with the outer surfaces of said fingers and throughout substantially the entire lengths thereof, the outer surface of each finger and the inner surface of the sleeve in contact therewith being contoured in a longitudinal direction to follow the curves of concentric arcs, whereby when the sleeve is longitudinally adjusted on the shell the said inner surfaces thereof will continue to maintain contact with the outer surfaces of the fingers throughout substantially the entire lengths of the latter.

2. A device as described in claim 1 in which the rear ends of the fingers are integrally united with the rear part of the shell by reduced neck portions adapted to bend when the fingers are contracted under the pressure applied by the sleeve.

3. In a shot pattern control device for a shotgun, a generally tubular shell adapted to be mounted on the muzzle end of the shotgun barrel and in axial alignment therewith, said shell having an externally threaded rear portion and a choke portion forward of the threaded portion, an adjustment sleeve encircling the shell and having internal threads cooperating with the rear portion of the shell for longitudinal adjustment of the sleeve on the shell, the wall of the choke portion of the shell having a plurality of slots extending longitudinally rearward from the forward end thereof to divide said portion into a plurality of annularly arranged forwardly extending segments adapted to have their forward ends moved radially inwardly to constrict the passage through the choke portion, said choke portion having an external surface which is circular in cross section at any point throughout its entire length, the outer surface of each of said sections and the inner surface of the sleeve immediately adjacent thereto being longitudinally curved in concentric arcs.
